UNITED STATES PATENT OFFICE.

WILLIAM CLARK MACE, OF MARSHFIELD, OREGON.

VENDING-MACHINE.

1,355,058.

Specification of Letters Patent.

Patented Oct. 5, 1920.

Application filed May 8, 1918. Serial No. 233,290.

To all whom it may concern:

Be it known that I, WILLIAM CLARK MACE, a citizen of the United States, and a resident of Marshfield, in the county of Coos 5 and State of Oregon, have invented certain new and useful Improvements in Vending-Machines, of which the following is a specification.

My invention relates to improvements in 10 vending machines, more particularly to those which vend liquids, and it consists in the combinations, constructions and arrangements herein described and claimed.

An object of my invention is to provide 15 a device which may be actuated by coins of different size or denomination to deliver a predetermined amount of liquid, said amount being in proportion to the value of the coin deposited.

Another object of the invention is to provide 20 a device which is normally locked, but which may be unlocked through the medium of the coin which has been deposited, so that the liquid may be withdrawn, and having means for subsequently automatically relocking the device.

A further object of my invention is to provide 25 a device of the type described having means for varying the amounts delivered for a given coin at will, as for instance, when the price of the liquid, such as gasoline, rises or falls in accordance with the market quotation.

Other objects and advantages will appear 30 in the following specification and the novel features of the invention will be particularly pointed out in the appended claims.

My invention is illustrated in the accompanying drawings forming part of this application, in which:

Figure 1 is a vertical section through a portion of the device,

Fig. 2 is a section on the line 2-2 of

Fig. 1,

Fig. 3 is a section on the line 3-3 of

Fig. 1,

Fig. 4 is a detail view showing the coin belt,

Fig. 5 is a sectional view substantially 50 along the line 5-5 of Fig. 4,

Fig. 6 is a detail sectional view showing a magnetic clutch,

Fig. 7 is a detail view of another magnetic clutch, and

Fig. 8 is a diagrammatic view of the actuating circuits.

In carrying out my invention I make use of a plunger rod 1 which may be attached to any suitable sort of plunger (not shown) for causing the delivery of the liquid. It 60 will be understood that the plunger rod 1 is similar to the plunger rods of those devices which when raised cause a given amount of liquid to be delivered, this amount being strictly in proportion to the upward 65 movement of the plunger rod. Such devices are in common use and the present invention lies in the unlocking means, the means for limiting the movement of the plunger, etc., as hereinafter disclosed, and 70 not in the plunger itself.

Referring now to the drawings, it will be seen that the rod 1 is provided with rack teeth 2 arranged to mesh with a pinion 3 on a shaft 4 which is mounted for revolution on a casing 5. The shaft 4 is in axial alignment with a shaft 6 which is designed to be connected with the shaft 4 by a magnetic clutch such as that shown in Fig. 6. 75 In this figure it will be seen that the shaft 80 4 is provided with magnets 7 having feed wires 8. These magnets are designed to act on slidable pins 9 carried by the shaft 6 and normally held retracted in the bores in which they are located by means of 85 springs 10. When, however, the magnets 7 are actuated, they draw the pins 9 forwardly into the holes 11, thereby connecting the shafts 4 and 6 so as to revolve together.

Carried by the shaft 6 is a worm 12 arranged to engage a worm wheel 13 on a shaft 14. The latter bears sprocket wheels such as those shown at 15 over which sprocket chains 16 run. These sprocket chains are endless and pass around sprocket 95 wheels 15' on a shaft 14' as shown in the drawing. At intervals the sprocket chains 16 bear lugs 17 for carrying forward the coin. The coin chute is shown at 18. Within the coin chute is a trap 19 which 100 is normally held by a spring 20 in such a position as to hold the coin until the trap has been released by means of one of the lugs 17, as will be explained later. The coins are held in position by means of a frame or 105 casing 21 which preferably forms a continuation of the coin chute 18. Any suitable receptacle for receiving the coins which have been deposited may be provided.

Referring now to Fig. 5, it will be seen 110 that just above the chains 16 I have provided a U-shaped cam plate 22 having an

inclined cam surface 22^a arranged to be engaged by a coin 23 so as to move the plate outwardly. The U-shaped cam plate 22 is provided with arms 22^b which bear normally on spring pressed detents or latch plates 24 on opposite sides of the rack bar or plunger 1, as shown in Fig. 5. The plunger is provided with recesses for receiving the ends of these latch plates which lock the plunger in position. Opposed to the cam plate 22 is a spring 25 having an inclined portion 25^a arranged to be engaged by the coin 23. The spring 25 is provided with two contacts 26 and 27 respectively. The former contact 26 is designed to engage a spring pressed contact 28 in the electrical connection with the binding post 29, for reciprocal movement of the spring 25. If, however, the spring 25 is pressed farther outwardly, then the contact 27 will engage a fixed contact 30 in electrical connection with the binding post 31. Facing the spring 25 is a bar 32 which is normally held in the position shown in Fig. 5 by means of the springs 33 but which may be pressed outwardly until it reaches the stops 34.

Revolably disposed in the base plate 35 is a screw shaft 36 having means such as the hexagonal portion 37 for rotating it around its axis. It will be understood that this shaft does not advance during rotation, that is to say, it is merely mounted to revolve in the base. Disposed on the screw shaft is a lower block 38 which is threaded to receive the shaft and which bears a movable stop member 39, see Fig. 7. The stop 39 is normally forced outwardly by means of a spring 40 but it may be retracted by means of a magnet 41 carried by the block, the end of the stop member 39 forming an armature. The stop member 39 is beveled at 39^a. The rack bar 1 has a fixed stop 42 arranged to engage the movable stop 39. A spring 43 is secured to the rack bar at one end and at the other end to the base plate 35. A second block 44 is also threaded to receive the screw shaft 36 and carries a fixed stop 45.

From the foregoing description of the various parts of the device, the operation thereof will be readily understood. Let us assume that two coins of different sizes are to be used, as for instance a silver dollar and a silver half dollar, and that gasoline is the liquid to be dispensed at 25¢ per gallon. If the half dollar is deposited in the coin chute, it is held by the trap 19. The handle 47 is now turned to revolve the shaft 6 which, through the medium of the worm 12 and the gear or pinion 13, operates the endless chain belt in the direction indicated by the arrow in Fig. 4. As soon as a lug 17 reaches the trap 19, it raises it and allows the coin to pass downwardly on the chain belt, where it is pushed forwardly by the

succeeding lug 17. The purpose of the trap 19 is to prevent the coin from being caught on a lug and jammed between the lug and the casing. The coin 23 is carried forwardly, that is to say from left to right in Fig. 5, and on reaching the cam plate 22 pushes it outwardly, swinging the detents 24 from their full line position shown in Fig. 5 to the dotted line position and thus freeing the rack bar 1 which is normally locked by these members. The coin also engages the spring 25 and closes the contacts 26 and 28, thus energizing the magnets 7 as shown in Fig. 8, and causing the shaft 4 to revolve. The revolution of the shaft 4 causes the plunger bar 1 to be raised through the medium of the gears 3 and the rack teeth 2.

The rotation of the handle 47 feeds the chain belt forwardly and at the same time causes the continued raising of the rack bar 1. When the 50¢ coin gets to the point 32^a the plunger with the stop pin 42 has engaged the stop 39. This stops the upward movement of the plunger rod 1 and at the same time, the coin slips laterally at the inclined portion 32^a so as to permit the spring 25 to come back into normal position. This breaks the circuit 26—28 and allows the plunger to return to normal position. The coin is deposited at the right hand end of the device as shown in Fig. 4. When the fixed stop 42 on the rack bar 1 reaches the stop 39 in Fig. 7, the bar can go no farther and it will have delivered liquid to the amount called for by the coin deposited, in this case, two gallons of gasoline.

If a dollar had been deposited, then the spring 25 would have been pushed back to the dotted line position shown in Fig. 8 and the contacts 27 and 30 would have been closed, thus energizing the magnet 41 and withdrawing the movable stop 39. When a dollar reaches the incline 32^a, it moves laterally and permits the spring 25 to move inwardly, i. e., toward the center of the carrier, breaking the contacts 27 and 30. The dollar, being of greater diameter than the smaller coin, will have moved the bar 32 against the tension of the springs 33 until it comes into engagement with the stops 34. The opposite edge of the dollar will hold the contact 26 against the spring contact 28 until the coin has passed entirely off from the carrier. In this case the rack bar would continue on until it reached the second stop 45, when four gallons would have been delivered. As soon as the required amount has been delivered, the coin 23 will pass out, thus permitting the spring 25 to resume its normal position and breaking the contacts 26—28 and 27—30. This will free the rack bar by the deenergization of the magnets 7 and the retraction of the pins 9 through the

medium of the springs 10, see Fig. 7. The rack bar will now be drawn downwardly into its original position by means of the spring 43. When the stop 42 reaches the 5 inclined end portion 39^a of the stop 39 it will push it inwardly far enough to pass the stop, when the latter will spring outwardly in the position shown in Fig. 7. When the rack bar reaches its lowest position, the 10 spring actuated detents 24 will assume their normal positions, shown in Fig. 5, thus locking the rack bar which can only be operated again by the deposit of a coin.

As stated above, the device is designed to 15 be used with any plunger capable of delivering a measured quantity of liquid. In Fig. 1, the casing 5 is shown as connected with the base plate 35 by means of posts 60, or any other suitable device. The cylindrical 20 portion 61 is designed to extend downwardly into association with the liquid receptacle (not shown). It may constitute the pump cylinder if desired.

It is obvious that the positions of the 25 blocks 38 and 44 may be shifted by turning the screw shaft 36 so that more or less of the liquid may be delivered as the price fluctuates. Obviously, also, blocks similar to that shown at 38, operated by circuits similar 30 to that shown in Fig. 8, could be added, and by placing other contacts similar to those shown at 27 and 30, additional coins could be used to deliver predetermined amounts of liquid other than that delivered when a silver 35 dollar or a half dollar is deposited, without departing in the least from the spirit of the invention or the scope of the claims.

I claim:—

1. In a liquid dispensing device, a plunger, means for normally locking the plunger, a coin carrier, means for delivering a coin to said carrier, means for operating the carrier to cause the engagement of the coin with the locking means for releasing the plunger, 45 and means adapted to be actuated by said carrier operating means in the presence of a coin for subsequently moving the plunger.

2. In a liquid dispensing device, a plunger, means for normally locking the plunger, 50 a coin carrier, means for delivering a coin to said carrier, means for operating the carrier to cause the engagement of the coin with the locking means for releasing the latter, means adapted to be actuated by said carrier operating means in the presence of a coin for subsequently moving the plunger, 55 and means for limiting the movement of the plunger to a predetermined distance.

3. In a liquid dispensing device, a plunger, means for normally locking the plunger, a coin carrier, means for delivering a coin to said carrier, means for operating the carrier to cause the engagement of the coin with the locking means for releasing the latter, 65 means adapted to be actuated by said car-

rier operating means in the presence of a coin for subsequently moving the plunger, and means dependent upon the size of the coin deposited for limiting the movement of the plunger to a predetermined distance. 70

4. In a liquid dispensing device, a plunger, means for normally locking the plunger, a coin carrier, means for operating the coin carrier to bring a coin into engagement with said locking means for releasing the same, and means operative in the presence of a coin for subsequently bringing the plunger into operative relation with the coin carrier operating means. 75

5. In a liquid dispensing device, a plunger, means for normally locking the plunger, a coin carrier, means for operating the coin carrier to bring a coin into engagement with said locking means for releasing the same, means including a magnetic 85 clutch for subsequently bringing the plunger into operative relation with the coin carrier operating means, and means actuated by the coin for operating the magnetic clutch. 90

6. In a liquid dispensing device, a movable plunger, means for normally locking the plunger, a coin carrier, means for delivering the coin to the carrier, means for operating the carrier, the movement of the carrier serving to bring the coin into engagement with the locking means for releasing the same, a pair of contacts adapted to be closed by the coin, and means including a magnetic clutch actuated by the closure of 100 the contacts for subsequently bringing the coin carrier operating means into operative relation with the plunger to move the latter. 105

7. In a liquid dispensing device, a movable plunger, means for normally locking the plunger, a coin carrier, means for delivering the coin to the carrier, means for operating the carrier, the movement of the carrier serving to bring the coin into engagement with the locking means for releasing the same, a pair of contacts adapted to be closed by the coin, means including a magnetic clutch actuated by the closure of 110 the contacts for subsequently bringing the coin carrier operating means into operative 115 relation with the plunger to move the latter, and a stop member for limiting the movement of the plunger.

8. In a liquid dispensing device, a movable plunger, means for normally locking the plunger, a coin carrier, means for delivering the coin to the carrier, means for operating the carrier, the movement of the carrier serving to bring the coin into engagement with the locking means for releasing the same, a pair of contacts adapted to be closed by the coin, means including a magnetic clutch actuated by the closure of 120 the contacts for subsequently bringing the coin carrier operating means into oper- 125 ation. 130

ative relation with the plunger to move the latter, stop members for limiting the movement of the plunger, one of said stop members being movable, and means actuated by the coin for shifting said movable stop member.

9. In a liquid dispensing device, a movable plunger, means for normally locking the plunger, a coin carrier, means for delivering the coin to the carrier, means for operating the carrier, the movement of the carrier serving to bring the coin into engagement with the locking means for releasing the same, a pair of contacts adapted to be closed by the coin, means including a magnetic clutch actuated by the closure of the contacts for subsequently bringing the coin carrier operating means into operative relation with the plunger to move the latter, stop members for limiting the movement of the plunger, one of said stop members being movable, and an electro-magnetic device adapted to be operated by the coin for withdrawing said movable stop member.

10. In a liquid dispensing device, a movable plunger, means for normally locking the plunger, a coin carrier, means for delivering the coin to the carrier, means for operating the carrier, the movement of the carrier serving to bring the coin into engagement with the locking means for releasing the same, a pair of contacts adapted to be closed by the coin, means including a magnetic clutch actuated by the closure of the contacts for subsequently bringing the coin carrier operating means into operative relation with the plunger to move the latter, stop members for limiting the movement of the plunger, one of said stop members being movable, an electro-magnetic device adapted to be operated by the coin for withdrawing said movable stop member, and means for adjusting the positions of either of said stop members.

WM. CLARK MACE.
